UNITED STATES PATENT OFFICE

CHARLES JOHNSON, OF RUDDELL, SASKATCHEWAN, CANADA

MOTOR-LICENSE HOLDER

Application filed August 5, 1929. Serial No. 383,565.

This invention relates to improvements in motor license holders and the like and the object of the invention is to devise an improved holder for motor license cards which will be of simple and inexpensive construction and which will provide for convenient attachment in any desired position upon the fabric lining the interior of the vehicle so that the license will be conveniently displayed.

A further object is to provide such a device which will enable the convenient and ready removal of the old license therefrom and the insertion of the new license.

The invention consists in the construction and arrangement, as hereinafter more particularly described, and illustrated in the accompanying drawings in which,

Figure 1 shows a perspective view of the complete device.

Figure 2 is a perspective view of an insert forming part of the device.

Figure 3 is an end edge elevation of the device.

Figure 4 is a central vertical transverse section through the complete device.

In the drawings like characters of reference indicate corresponding parts in each figure.

The improved device comprises a rectangular sheet-metal casing 10 the side and bottom marginal edges of which are turned over towards the front face of the casing at 11 and 12 respectively to form guideways for the reception and retention of an insert, as will be presently explained.

Secured to the back of the casing 10 adjacent the top thereof are two pins 13 which extend downwardly beyond the bottom of the casing, the lower extremities of these pins being bent rearwardly as at 14.

Associated with the casing is a rectangular sheet-metal insert 15 the side and top marginal edges of which are turned over towards the front face of the insert, as at 16 and 17, to form guideways at the front of the insert.

Mounted within the guideways of the insert is a sheet of celluloid or other suitable transparent material 18 and removably held within the insert behind the sheet 18 is the

license card 19 which is visible through the sheet 18.

In using the device the license card 19 is inserted within the insert and the insert is then inserted within the holder being removably held in place in the guideways in the casing formed by the turned over marginal edges 11 and 12. The device is readily attached within the vehicle by simply pushing the pins 13 through the fabric lining the vehicle so that the device is securely held in place. By bending the pins 13 slightly rearwardly at 14 it obviates the likelihood of the lower ends of these pins projecting through the fabric.

When it is desired to replace the old license card with a new card, it is only necessary to withdraw the insert from the device, remove the old license card from the insert, replace it with a new one, and re-insert the insert within the casing.

From the foregoing it will be apparent that the invention provides an improved device of the character described whereby the objects set forth have been attained.

Various modifications may be made in this invention without departing from the spirit thereof or the scope of the claim, and therefore the exact forms shown are to be taken as illustrative only and not in a limiting sense, and it is desired that only such limitations shall be placed thereon as are disclosed in the prior art or are set forth in the accompanying claim.

What I claim as my invention is:

A device of the character described comprising a rectangular casing and a removable rectangular insert therefor, the casing comprising a sheet-metal plate having its side and bottom marginal edges turned over towards the front face of the plate to form guideways for the reception and retention of the insert, spaced apart pins secured to the back of the casing adjacent to the top thereof adapted to penetrate and support the casing upon a supporting fabric, the insert comprising a sheet-metal plate having its side and top marginal edges turned over towards the front face of the plate to form guideways, a sheet of transparent material mounted

within the guideways in the insert, and a sheet of material removably mounted within the insert behind the aforesaid sheet of transparent material and visible therethrough, the 5 insert adapted for removable engagement within the guideways in the casing.

In witness whereof I have hereunto set my hand.

CHARLES JOHNSON.
